UNITED STATES PATENT OFFICE

DIRK B. ZIGTEMA, OF WICHERT, ILLINOIS

LIFE SAVING DEVICE

Application filed May 23, 1930. Serial No. 455,014.

This invention relates to life saving apparatus and has for an object the provision of means to facilitate the escape of persons from disabled submarine and other vessels.

An object of the invention is to provide a hollow buoyant member capable of accommodating a number of persons and normally housed within a chamber extending downward from the deck of the vessel, together with means to release the buoyant member and maintain contact with the vessel after the buoyant member is released, so that the said member may be returned to the vessel for further use.

Another object of the invention is the provision of means whereby the buoyant member may be returned to the vessel through the medium of means operated either from the vessel or from said member, whereby the member may be returned to the vessel for further use in the event that persons left aboard are disabled.

With the above and other objects in view, the invention further includes the following novel features and details of construction, to be hereinafter more fully described, illustrated in the accompanying drawings and pointed out in the appended claims.

In the drawings:—

Figure 1 is a top plan view of a submarine vessel equipped with the invention.

Figure 2 is an enlarged fragmentary sectional view on the line 2—2 of Figure 1.

Figure 3 is a section on the line 3—3 of Figure 2.

Figure 4 is a view similar to Figure 2 with the buoyant member released.

Figure 5 is a top plan view of the buoyant member.

Figure 6 is a like view looking down into the chamber.

Figure 7 is a fragmentary side view illustrating one of the positioning lugs of the buoyant member.

Figure 8 is a sectional view on the line 8—8 of Figure 4.

Figure 9 is a fragmentary sectional view taken through a portion of the submarine vessel and showing the life saving apparatus in elevation.

Figure 10 is a fragmentary sectional view through the upper part of the buoyant member.

Figure 11 is an enlarged fragmentary sectional view on the line 11—11 of Figure 9.

Figure 12 shows a fragmentary elevation of one end of the cable, and a cross sectional view of said cable.

Figure 13 is a fragmentary sectional view through one end of the cable drum.

Figure 14 is an end view of the drum.

Figure 15 is a fragmentary sectional view illustrating a slightly modified form of the invention.

Referring to the drawings in detail where-in like characters of reference denote corresponding parts, the reference character 16 represents the hull of a submarine or other vessel and 17 the deck.

Extending downwardly from the deck 17 is a chamber 18, the walls 19 of which are shown as cylindrical and tapering to a point at the bottom of the chamber. The chamber 18 is preferably positioned in a transverse bulkhead 20 which separates two compartments of the vessel and the vessel may be provided with two of such chambers positioned upon opposite sides of the longitudinal center of the vessel, or in any other convenient place. Each of the chambers and the cooperating parts of the device are of like construction, so that only one of the devices will be described. While two are shown, any suitable number may be provided.

Normally positioned within the chamber 18 is a hollow buoyant member 21. This member is preferably formed of inner and outer walls 22 and 23 respectively so as to provide an annular space 24. This space may be airtight to provide increased buoyancy, or it may be filled with cork, or some other light material. Vertically disposed ribs 25 connect the walls 22 and 23 so as to resist pressure of the water.

The buoyant member is provided with 95 openings 25, preferably two of these openings being provided, the openings in the inner wall 22 being in register with the openings in the outer wall 23, as shown in Figure 11 of the drawings. These open-

ings are surrounded by a frame 26 which connects the inner and outer walls and this frame is provided with guides 27 which receive the opposite edges of a door or closure 28. This door slides in the guideways and the latter are provided with rubber or other waterproof packing 29 so as to form a leak-proof joint. The doors 28 are provided with oppositely extending handles 30 which are disposed within the space between the walls 22 and 23, whereby the doors may be operated from either the inside or the outside of the buoyant member. The bottom of the buoyant member is provided with a platform or floor 31.

15 The wall 19 of the chamber 18 is likewise provided with openings 32. These openings are arranged upon opposite sides of the chamber so that one of the openings will be upon one side of the bulkhead 20 and the other opening will be upon the opposite side of the bulkhead. This permits entrance into the chamber 18 from either side of the bulkhead, so that should one compartment be flooded, 20 occupants of the vessel may enter from the other compartment. The openings 32 are normally closed by doors or closures 33 and the latter are provided with oppositely extending handles 34, whereby the doors may be manipulated from either side of the wall 19. Thus, persons upon either side of the bulkhead 20 may enter the buoyant member through the openings 32 and 25.

25 The top of the buoyant member is closed by a cover 35, and this cover is reinforced by channel bars 36, so as to resist pressure of the water. The cover 35 extends beyond the outer wall 23 of the buoyant member and is provided with a compressible gasket or packing 37 which engages an annular flange 38 extending around the upper open edge of the chamber 18. When the gasket is forced into close contact with the flange 38 a leak-proof joint will be provided.

30 Operating in guides 39 which connect the inner and outer walls of the buoyant member are bolts or latches 40. These latches are yieldingly forced outward by means of springs 41 and are adapted to be received in sockets 42 disposed adjacent the top of the chamber 18. The outer ends of these bolts or latches are beveled so as to engage the beveled edge of the flange 38, and when the buoyant member is forced into the chamber 18, these latches will automatically engage within the sockets 42. Levers 43 are connected with these latches and are pivotally mounted as shown at 44 so that the latches may be manually retracted from within the buoyant member. The cover 35 is provided with a hatchway 45 which is normally closed by a hatch 46. A pivotally mounted clamping member 47 serves to hold the hatch in closed position.

35 In order to insure register of the openings

25 with the openings 32 when the buoyant member is positioned within the chamber 18, a cam shoulder or rib 48 extends around the inner face of the wall 19. This rib or shoulder is provided with diametrically located, 70 upwardly extending, pointed portions 49 and diametrically located, downwardly extending, pointed portions 50. The portions 50 are arranged at one hundred and eighty degrees with respect to the portions 49. Extending 75 from the outer wall 23 are pointed lugs 51 and when the buoyant member is inserted in the chamber 18 these lugs will engage upon either side of the pointed portions 49 of the cam shoulder 48. The lugs are so positioned 80 that when the buoyant member is moved downward and the lugs positioned within the pointed portions 50, the openings 25 and 32 will be directly opposite one another. This is true irrespective of which side of the 85 pointed portions 49, the lugs 51 engage. The walls 19 of the chamber 18 are provided with check valves 52. These valves are located below the lower edge of the openings 25 and 32, and when the buoyant member is forced 90 into the chamber 18, water therein will escape through these check valves so that the level of the water remaining in the chamber will be below the lower edges of the openings 95 and 32.

95 Extending through a suitable packing 53 provided in the lower pointed end of the buoyant member is a cable 54. This cable also extends through a packing member 55 in the lower pointed end of the wall 19, so that the 100 cable may be run through these packing members and a leakproof joint be maintained. The cable extends downwardly within a compartment 55 provided within a housing 56. This housing is arranged at the bottom of the chamber 18 and carries a drum 57 which is fast on a shaft 58. Freely rotatable on the shaft 58 is a brake drum 59 and this drum is locked to the shaft when rotated in one direction through the medium of an overrun clutch 105 60. A brake band 61 engages the drum and its tension is regulated by means of a turn-buckle 62. When the shaft is rotated to wind the cable on the drum 57, the brake drum 59 will be free of the shaft 58, but when the 110 drum rotates in a direction to unwind the cable, the brake drum will be fast with the shaft and the brake band will be so adjusted 115 as to permit of a free unwinding movement without back lash of the cable.

120 The drum 57 may be operated by any suitable means, such as a motor 63 and a belt and pulley drive 64. If desired, a crank handle 65 may be engaged with the shaft 60 to manually rotate the drum. Normally, this crank handle is mounted in hangers 66, at one side of the housing 56. The housing is provided with openings 67 which are normally closed by doors 68. Conductor wires 69 may lead 125 in through the housing as shown in Figure 130

2 for electrical connection with the motor 63.

Preferably, the cable 54 has electric cables 70 and 71 embedded therein. These cables carry conductor wires 72 and 73 which extend into the buoyant member so that the latter may have telephonic and other electrical communication with the sunken vessel when the buoyant member is released.

The end of the cable passing into the buoy-

10 ant member may be connected with a hand operated windlass 74 whereby an occupant of the buoyant member may wind the cable upon this windlass and return the buoyant member to the vessel. This is especially useful where it is necessary or desirable to return 15 to the submarine or sunken vessel after the buoyant member has made one or more trips to the surface.

Extending inward through the top or cover 20 35 of the buoyant member are hose couplings 75. These couplings are secured in brackets 76 and their upper ends are normally closed by caps 77. An air hose may be attached to the outer end of either or both of these couplings, and a similar hose may be attached to their inner ends and may extend through the openings 25 downward to the sunken vessel. The lower end of the hose may be attached to the air supply tubes usually found 30 in submarine vessels for the distribution of a supply of air to the various compartments of the vessel.

In order to provide a supply of current to the cables 70 and 71, the cable 59 has one of its 35 ends secured to the drum 57 as shown at 78 in Figure 13 of the drawings. The conductor wires 72 and 73 are connected to spring contacts 79 carried by the drum 57 and these contacts wipe against distributor rings 80 which 40 are carried by a stationary support 81. The rings 80 are connected with a suitable source of current.

In Figure 15, the coiled spring 82 is positioned within the bottom of the chamber 18 and bears against the lower end of the buoyant member, so that when the latter is released through operation of the latches 42, this spring will exert an upward pressure against the bottom of the buoyant member 50 and insure its initial upward movement by counteracting suction within the chamber 18.

The invention is susceptible of various changes in its form, proportions and minor details of construction and the right is herein 55 reserved to make such changes as properly fall within the scope of the appended claims.

Having described the invention what is claimed is:—

60 1. In a submarine vessel, a chamber open at the top and extending downward from the deck of the vessel, watertight doors providing access to said chamber from the interior of the vessel, a watertight hollow buoyant member adapted to be positioned within said chamber, means carried by said member to

close the upper end of the chamber, means to releasably lock said member within said chamber, watertight doors for the buoyant member, a cam shoulder extending around the inner wall of said chamber, and lugs extending from the buoyant member to engage said shoulder and guide and position the buoyant member to bring the doors of the latter into register with the doors of the chamber.

65 2. In a submarine vessel, a chamber extending downward from the deck of the vessel having a beveled flanged open upper end, watertight doors providing access to said chamber from the interior of the vessel, a watertight hollow buoyant member adapted 70 to be positioned within said chamber, means carried by said chamber to close the open upper end of the chamber, radially movable spring-pressed means to releasably and automatically lock said member within said chamber and adapted to cooperate with the flanged upper end of the chamber during the locking action of the member within said chamber, watertight doors for the buoyant member and interengaging means between said member 80 and the walls of said chamber to bring the doors of the buoyant member into register with the doors of the chamber.

75 In testimony whereof I affix my signature.
